US0D1105722S

(12) **United States Design Patent** (10) Patent No.: **US D1,105,722 S**
(45) Date of Patent: ** Dec. 16, 2025

(54) **OUTSOLE BOTTOM**

(71) Applicant: **Skechers U.S.A., Inc. II**, Manhattan Beach, CA (US)

(72) Inventor: **Jason MacMaster**, Manhattan Beach, CA (US)

(73) Assignee: **Skechers U.S.A., Inc. II**, Manhattan Beach, CA (US)

(**) Term: **15 Years**

(21) Appl. No.: **29/973,750**

(22) Filed: **Nov. 18, 2024**

Related U.S. Application Data

(63) Continuation-in-part of application No. 29/956,040, filed on Aug. 5, 2024.

(51) **LOC (15) Cl.** **02-04**

(52) **U.S. Cl.**

USPC **D2/957**; D2/951; D2/959; D2/960

Primary Examiner — T Chase Nelson

(74) Attorney, Agent, or Firm — Marshall A. Lerner; Steven J. Kim; Kleinberg & Lerner, LLP

(57) **CLAIM**

The ornamental design for an outsole bottom as shown and described.

DESCRIPTION

FIG. 1 is a front perspective view of the outsole bottom in accordance with my new design;

FIG. 2 is a left view thereof;

FIG. 3 is a right view thereof;

FIG. 4 is a front view thereof;

FIG. 5 is a rear view thereof;

FIG. 6 is a top view thereof; and,

FIG. 7 is a bottom view thereof.

The dash-dash broken lines shown in the drawings represent environmental structure showing parts of the upper and shoe midsole periphery as well as portions of the outsole bottom that form no part of the claimed design.

1 Claim, 7 Drawing Sheets
